UNITED STATES PATENT OFFICE

JAMES A. SHAFER, OF EAST CLEVELAND, OHIO, ASSIGNOR TO NATIONAL MALLEABLE AND STEEL CASTINGS COMPANY, OF CLEVELAND, OHIO, A CORPORATION OF OHIO

LOCK

Application filed May 26, 1928. Serial No. 280,668.

The present invention has been evolved in connection with the development of a lock for holding closed the discharge doors of railway hopper cars and for convenience 5 such an embodiment will be described for the purposes of illustrating the principles involved.

Locks of this character must be unfailingly reliable under the difficult conditions 10 of railway use and yet economy of manufacturing costs is a matter of importance on account of the large number of locks used. The doors must be held closed not only when the doors are new and more or less well 15 fitted but also after they are worn and distorted in use. It is desirable, therefore, that the lock shall be designed to hold the door effectively locked in closed position under all conditions which are likely to exist. The 20 invention provides in the preferred embodiment thereof a lock which operates with a wedging action in a manner to insure effective locking with the possibility of forcing 25 the door closed by means of the operation of the lock. The operation of the wedging means is such that if, because of distortion of parts or otherwise, the closed position of the door varies somewhat from its normal or original completely closed position, it can, 30 nevertheless, be securely locked.

The present invention provides an effective reliable lock convenient of operation and one which can be economically manufactured and expeditiously applied.

35 The nature and objects of the invention will be better understood from a description of the particular selected embodiment thereof for the purpose of which description reference should be had to the accompanying 40 drawings forming a part hereof and in which—

Figure 1 is a diagrammatic side elevation of a hopper car with a lock embodying the invention applied thereto,

45 Figure 2 is a central transverse section of the car shown in Fig. 1,

Figure 3 is a detail side elevation, partly in section, of said lock,

50 Figure 4 is a detail horizontal section on the line IV—IV of Fig. 3,

Figure 5 is a vertical section on the line V—V of Fig. 3,

Figure 6 is an end elevation of Fig. 3, as viewed from the direction indicated by the arrow VI in Fig. 3,

55

Figure 7 is a perspective view of the latch lock retainer,

Figure 8 is a perspective view of the latch lock, and

Figure 9 is a view similar to Fig. 3, but 60 with the outside housing plate removed, the latch in the raised position and the door partly open.

Referring to Fig. 1 there is illustrated a hopper car, the hoppers 5 of which are 65 closed by discharge doors 6 extending transversely of the car. The doors are arranged in pairs, the two doors of each pair being connected by a door spreader 7 at their lower edges, which spreader is engaged by locks 70 8 at either end thereof for holding the doors tightly closed.

The lock shown for the purposes of illustrating the principles of the invention comprises a two-part housing with a latch 10 75 slidably mounted therein and engageable with a suitable flange 11 of the door spreader 7 and serving as a keeper. The flange 11 may conveniently be formed to lie at an acute angle to the plane of the door, as shown in Fig. 80 3, but this is not essential. The door spreader is suitably fitted around the marginal flange of the door as will be readily understood.

The inner part 12 of the housing is formed with three bosses 13 which extend against 85 and space the body of the housing from the side wall of the car body. The outer part 14 is formed with a boss 15 which aligns with the uppermost boss 13 and projects into a recess 16, in the inner housing part 12, and 90 with bosses 15' which align with the two other bosses 13. These bosses are centrally apertured to receive the rivets 17 for securing the housing parts together and to the wall of the hopper. A projecting flange 35 on 95 the outer housing member 14 engaging a recess 36 in the inner housing member and hereinafter described acts to align and space the housing members.

The latch 10 comprises a central web 20, 100

Fig. 5, surrounded on each side thereof by a peripheral reinforcing flange 21 and having oppositely projecting bosses or trunnions 23, 24 which are received in guideways 25, 26 in the inner and outer housing members respectively. The trunnions are preferably elongated as shown to afford extended contact with the guideways. Referring to Fig. 3, it will be seen that the left side of the upper trunnions 23 and the right side of the lower trunnions 24 are parallel to the direction of movement of the latch in the guideways of the housing. These faces of the trunnions are the ones which bear against the guideways and resist the stresses of use tending to open the doors when the parts are in locked relation. The guideways 25 and 26 are preferably curved at their upper ends in order to increase the gather and permit preliminary catching of the door with the door farther from its tightly closed position than would be possible with straight guideways.

It will be noted that the operative face of the latch where it engages the door spreader, as indicated at 28, lies at an acute angle to the direction of movement of the latch in the guides 25, 26. By this arrangement when the door approaches closed position, but is still open a substantial distance, the flange 11 of the door spreader can be engaged by the face 28 of the latch 10 and can, therefore, be securely held in this position or it can be forced to tightly closed position by forcing the latch downwardly thus using the lock as a wedging means for completely closing the door. The wedge arrangement makes possible an effective locking of the door in tightly closed position even if parts are somewhat distorted which cannot be obtained by a lock adapted to hold the door in one position only. The latch and keeper are formed to provide an extended bearing to insure an effective engagement when the door is locked.

The lower end of the latch 10 may conveniently be formed on a curve such that as the door is closed the latch will be lifted automatically by engagement of the flange 11 with the curved lower edge.

It is desirable to provide suitable means whereby the latch 10 may be forcibly retracted from locking position to release the door and forcibly moved to locking position whereby the door may be forced to fully closed position using the lock parts in the operation. As shown, the latch is formed with a suitable apertured extension 29 and the inner housing member 12 is formed with a number of ledges 29' whereby a pinch bar such as is ordinarily carried by operatives may be introduced through the extension and into engagement with the ledges to force the latch to and from closed position, as suggested in Fig. 5. The two positions of the pinch bar indicated in dot and dash lines illustrate respectively the locking and releasing operations in which the

bar is fulcrumed for successive movements against successive ledges 29'. It will be noted that in both operations the operative stands in a safe position at the side of the car and reaches straight inwardly. Furthermore his pinch bar engages the relatively stationary lock and not the swinging door. He is, therefore, in no danger when dumping the load.

In order that the housing may be substantially dirt and weather proof to protect the operating parts, the outer housing member 14 is provided with an inwardly directed marginal flange 14' extending around its upper portion from the point 14' at the right in Fig. 3 to the lower left hand rivet position, and engaging against the outer face of the inner housing member. At the lower end of the guideway 26 in the outer housing member, a small hole 26' is provided to permit dirt and water to escape.

A suitable locking means is provided for holding the latch 10 in door locking position. As shown a latch lock 30, shown in perspective in Fig. 8, is movable transversely of the housing, the inner face of this latch lock and the adjacent edge of the latch 10 being provided with teeth 31, 32 which interengage to hold the latch firmly in any one of several adjusted positions. A suitable guideway for the latch lock 30 is afforded by providing the outer housing member 14 with an inwardly directed flange 35, as best shown in Figs. 4 and 9. The inner end of the flange projects into a recess formed at 36 in the inner housing member 12. The latch lock 30 is formed at its inner end with oppositely disposed lugs 37 which engage stops formed in the plane of the web of the housing 14 in the outer ends of the guideway 35 to prevent complete removal when the latch lock is withdrawn to unlock the latch 10. The latch lock 30 is, therefore, well housed for movement transversely of the plane of the housing and of the latch 10 for engagement and disengagement with the teeth 32 of said latch.

In order to facilitate forcibly retracting the latch lock 30, recesses 40 are formed therein for engagement by a pinch bar as indicated in dot and dash lines in Fig. 4. The pinch bar may be engaged in first one and then the other recess for two successive operations to retract the latch lock. A projection 41 is shown in Figs. 3 and 4 as formed on the housing which may serve as a fulcrum for the operation.

The ends of the teeth 31 and 32 of the latch lock 30 and of the latch 10 are chamfered as indicated most clearly at 31' in Fig. 8 and 32' in Fig. 9 to facilitate pushing the latch lock into locking position when the parts are brought into approximate alignment. The spacing of the teeth 31 and 32 and the angle between the direction of movement of the wedge and its keeper engaging face are so proportioned as to give the desired accuracy

of adjustment of the final closed position of the doors.

Preferably retaining means is provided to prevent the possibility of the latch lock 30 jarring out of locking position. As shown, a latch lock retainer 43 is slidably mounted in ways 44 formed in the outer face of the housing to move to and from position overlying the end of the latch lock 30. As shown, this retainer is movable vertically and gravitates to lock retaining position. In its lowermost position its lower end engages a projection 45, Figs. 3 and 8, formed on the latch lock 30. When it is lifted and the latch lock 30 is retracted, its lower end will drop into a slot or notch 46 in the upper face of the latch lock to retain the latter in retracted position. The outer wall of the recess 46, however, is tapered as may be seen in Fig. 6 so that if the latch lock 30 is, in fact, forcibly pushed inwardly without manually lifting the retaining member, said retaining member will be automatically lifted by riding up on said tapered wall of the recess.

The retaining member and the latch lock may be marked with the words "Lift" and "Pull" respectively to indicate the operations necessary in opening the car door, and the latch may be marked with the words "Pinch bar" to indicate the position of inserting a bar for operating the latch.

The several parts of the lock interengage in such a way that none of the moving parts can be removed after the lock is riveted to the hopper by the three securing rivets. This will be better understood from a description of the manner of assembly. When assembling the lock the retaining member 43 is first introduced into the guideways 44 in the outer housing member, the latch lock 30 is inserted from the rear into the same housing member, and then the latch 10 and the inner housing member are assembled and the lock parts connected and secured to the hopper wall by means of the rivets 17.

The foregoing description is illustrative merely and is not intended as defining the limits of the invention.

I claim:

1. In a hopper car having a hopper and transversely extending discharge doors, in combination, a transverse spreader connecting the doors and projecting beyond the lateral end thereof, and a lock comprising a housing secured to the outer face of the hopper in spaced relation thereto and a latch in said housing engageable with the projecting end of said spreader bar to lock the door in closed position, said latch and housing being formed respectively with an extension and a series of ledges to be engaged by a pinch bar whereby said latch can be forced to and from locking position, substantially as described.

2. In a lock for the discharge door of a

hopper car, the combination with a keeper to be carried by the door and presenting a latch engaging surface, of a latch to be carried by the car body and movable bodily at an acute angle to the face of the keeper, to engage the same, substantially as described.

3. In a lock for the discharge door of a hopper car, the combination with a keeper to be carried by the door and presenting a latch engaging surface lying at an acute angle to the plane of the door, of a latch to be carried by the car body and movable bodily at an acute angle to engage the face of the keeper, substantially as described.

4. In a lock for the discharge door of a hopper car, the combination with a keeper to be carried by the door and presenting a latch engaging surface, of a housing to be carried by the car body, and a latch movable in said housing on a line lying at an acute angle to the latch engaging surface of the keeper and engageable therewith to lock the door in closed position, substantially as described.

5. In a lock for the discharge door of a hopper car, the combination with a keeper to be carried by the door and presenting a latch engaging surface, of a housing to be carried by the car body, and a latch movable in said housing on a line lying at an acute angle to the latch engaging surface of the keeper and engageable therewith to lock the door in closed position, said latch and housing being formed respectively with an extension and a series of ledges to be engaged by a pinch bar whereby said latch can be forced longitudinally against the angularly positioned face of the keeper to force the door to closed position, substantially as described.

6. In a lock for the discharge door of a hopper car, the combination with a keeper to be carried by the door and presenting a latch engaging surface lying at an acute angle to the plane of the door, of a housing to be carried by the car body, a latch movable in said housing on a line lying at an acute angle to the latch engaging surface of the keeper and engageable therewith to lock the door in closed position, said latch and housing being formed respectively with an extension and a series of ledges to be engaged by a pinch bar whereby said latch can be forced longitudinally against the angularly positioned face of the keeper to force the door to closed position, and a locking device engageable with said latch for holding it in one of several adjusted positions, substantially as described.

7. In a lock for the discharge door of a hopper car, the combination with a keeper to be carried by the door and presenting a latch engaging surface, of a housing to be carried by the car body, a latch movable in said housing on a line lying at an acute angle

to the latch engaging surface of the keeper and engageable therewith to lock the door in closed position, said latch and housing being formed respectively with an extension and 5 a series of ledges to be engaged by a pinch bar whereby said latch can be forced longitudinally against the angularly positioned face of the keeper to force the door to closed position, and a latch lock movable in said 10 housing transversely of said latch, said latch lock and latch having interengaging teeth for locking the latch in any of several positions, substantially as described.

8. In a lock for the discharge door of a 15 hopper car, the combination with a keeper to be carried by the door and presenting a latch engaging surface lying at an acute angle to the plane of the door, of a housing to be carried by the car body, a latch movable in said 20 housing on a line lying at an acute angle to the latch engaging surface of the keeper and engageable therewith to lock the door in closed position, said latch and housing being formed respectively with an extension and a 25 series of ledges to be engaged by a pinch bar whereby said latch can be forced longitudinally against the angularly positioned face of the keeper to force the door to closed position, a locking member movable in said 30 housing transversely of said latch, said locking member and latch having interengaging teeth for locking the latch in any of several positions, and a retaining member normally 35 gravitating to position to prevent retraction of the locking member, substantially as described.

9. In a lock for the discharge door of a 40 hopper car, the combination with a keeper to be carried by the door and presenting a latch engaging surface of a housing comprising a 45 pair of mating sections having opposed inwardly facing guideways, and a latch comprising a web member having lateral projections engaging the guideways and having an end portion projecting beyond the housing to engage the keeper, substantially as described.

10. A lock of the character defined in the 50 preceding claim wherein the guideways are curved to increase the gather of the latch during its operating movement, substantially as described.

11. In a lock for the discharge door of a 55 hopper car, the combination with a keeper to be carried by the door and presenting a latch engaging surface, of a housing comprising a 60 pair of mating sections formed to provide a guideway in the plane of the housing for a latch and a guideway transversely to the plane of the housing, a latch in said first mentioned guideway engageable with the keeper and a latch lock in the second guideway cooperating with said latch to lock the same in operative position, substantially as described.

12. In a lock of the character described, the

combination with a keeper to be carried by a door, of a latch movable by gravity at an angle to the face of the keeper to provide a wedging action thereagainst, and means for locking the latch in any one of a plurality of 70 positions substantially as described.

13. In a lock of the character described, the combination with a keeper to be carried by a door of a latch movable at an angle to the face of the keeper and a housing for said latch, said latch and housing having abutments to be engaged by a pinch bar for forcing said latch to and from locking position, substantially as described.

14. In a lock for the discharge door of a 80 hopper car, the combination with a keeper of a housing and a latch movable in said housing, said housing and latch having abutments adapted to be engaged by a pinch bar inserted at substantially a right angle to the side 85 of the car to actuate said latch, substantially as described.

15. In a lock for the discharge door of a 90 hopper car, the combination with a keeper of a housing and a latch movable in said housing, said housing comprising two face plates, one of which is provided with a flange extending around the upper portion thereof to exclude weather and dirt, substantially as described.

16. In a lock for the discharge door of a 95 hopper car, a door abutment and a swinging discharge door, a latch mounted on said abutment for movement in a straight line at an angle acute to the door abutment, and means for locking said latch in any one of a plurality of door engaging positions.

17. In a lock for the discharge door of a 100 hopper car, a door abutment and a swinging discharge door, a latch mounted on said abutment and movable downwardly and in a straight line at an angle to the plane of the door to engage and secure said door in closed position and means for locking said latch in any one of a plurality of door engaging 110 positions.

In testimony whereof, I have signed my name to this specification this 23rd day of May, 1928.

JAMES A. SHAFER.
